UNITED STATES PATENT OFFICE

2,099,246

METAL TAPPING TOOL

Harry Raffles, Chicago, Ill.

Application March 27, 1937, Serial No. 133,352

1 Claim. (Cl. 145—61)

This invention relates to so-called metal tapping sets and more particularly to tools therefor, said tools comprising a shock absorbing protective cap and tool shanks arranged for interchangeable use with said protective cap.

The invention is adapted for tools forming a part of toy metal tapping sets, which sets comprise small plates of thin sheet brass or other suitable material on which are outlined designs which may be followed by tapping the outline of the designs with various tools as desired, to puncture or indent the material and thereby provide a suitable artistic effect. Thin blocks of wood or other material are provided on which the sheets of brass may be mounted, and a suitable hammer is also furnished with the set, together with a plurality of tool shanks and an interchangeable protective cap therefor.

The tapping tools ordinarily used cause considerable disagreeable noise which it is desirable to eliminate, also, they tire the hand of the user. It is therefore an object of the present invention to provide a set of tool shanks and an interchangeable protective cap therefor in which the noise of tapping is largely eliminated and in which the shock of the hammer blow is not transmitted to the hand of the user and therefore does not tire the hand.

These sets are ordinarily used by small children, and it is important to prevent injury to the hands of the user. It is therefore another object of the invention to provide a protective cap of comparatively large size relative to the tool and so constructed that the hammer will ordinarily not slip on the tool head.

A further object is the provision of a peculiar type of protective cap for small tool shanks in which a suitable sound absorbing cushion is provided for the striking end of the protective cap, and also in which the shanks do not come into striking engagement with the metal of the protective cap but are protected therefrom by suitable shock absorbing and noise preventing means.

A further object is the provision of a device of the character described which is of few parts, cheap to manufacture, efficient in use, and which will not easily get out of order.

Further objects will be apparent from the specification and the appended claim.

In the drawing:

Figure 1 is a full-sized side elevation of the cap and one of the interchangeable tool shanks associated therewith, the shank being provided with a so-called chisel point;

Fig. 2 is an enlarged axial sectional view through the cap illustrated in Fig. 1;

Fig. 3 is an enlarged view of one of the interchangeable shanks having a comparatively sharp point; and

Fig. 4 illustrates one of the wooden blocks which is furnished with the tapping set and provided with a thin sheet of metal thereon, on which is outlined a suitable design to be tapped.

Referring to the drawing in detail, the embodiment illustrated comprises a cap portion 1 and a shank 2 telescopically mounted thereon. The cap comprises a base portion 3 which is preferably greatly enlarged at its upper end, as indicated at 4, and provided with a depending 10 tapered portion 5 which is only slightly larger at its lower end than the shank to be inserted therein. The upper face of the cap is provided with a shallow large diameter counterbore 6, and a comparatively thick plug 7 of rubber or similar resilient material is inserted in the bore 6 and preferably overlaps the upper surface of the base 4 to provide a large thick striking surface for the hammer, which, as previously mentioned, is furnished with the tapping set.

The cap is also provided with a small diameter axial bore 8 in its opposite end, which bore is of sufficient diameter to provide a sliding fit over the shanks 2 and 2^a, or other interchangeable shanks which may be provided, whereby 30 the cap may easily be retained on the shanks, although the shanks are freely movable in the bore 8 when the cap is struck with the hammer. The elongated bore 8 preferably extends to a point closely adjacent the counterbore 6 35 to provide a thin partition 9 therebetween. A snugly fitting plug 10 of rubber or similar material having shock absorbing and noise preventing characteristics is snugly pressed into the bore 8 and adjacent the partition 9 so that when 40 any of the shanks are telescoped into the cap the blunt end of the shank will be separated from partition 9 by the plug 10.

As previously stated, any number of shanks may be provided in accordance with the requirements 45 of the particular toy set, and the cap is adapted to interchangeably accommodate any of the shanks. The shanks may be provided with various types of working ends or points, such as indicated at 11 and 12. Also, a plurality of wooden 50 blocks 13, together with a supply of metal plates 14, having suitable designs thereon, may be provided in a set.

In use, a suitable shank is selected for a desired portion of the design, and the cap is tele- 55

scoped thereon. The tool is then used by tapping on the rubber pad 7 of the cap with the hammer to perforate or indent the design. When one portion of the design is completed, any other suitable shank included with the set may be used in connection with the cap on other portions of the design.

It will be apparent that the invention provides a device which is substantially shock- and noise-proof and which provides maximum safety and efficiency in use.

The tools are used by gripping the shank below the cap and the present invention provides a device in which the comparatively heavy cap is resiliently separated from the shank to prevent tiring the hand of the user by the transmission of the shock of impact of any metal part thereto, and also in which the hammer blow is suitably cushioned.

20 The cap is comparatively quite heavy in order that its momentum when struck by the hammer will be transmitted to the shank through the resilient plug 10. By this means no shock of any metallic impact is ever applied to the shank.

Thus the hammer blow and consequent momentum of the cap provides a cushioned pressure of the point of the tool against the work instead of a quick cutting blow and the artistic effect produced by the action of the tool on the work piece is greatly enhanced.

Modifications may be made by those skilled in the art, and it is desired, therefore, that the invention be limited only by the prior art and the scope of the appended claim.

Having thus described this invention, what is claimed and desired to be secured by Letters Patent is:

A tool of the character described comprising the combination of a tool-shank with a working end, the other end being blunt, a protective cap for said blunt end functioning as a blow-receiving member therefor, said cap being provided with a bore of such diameter that the blunt end of the shank may freely fit and slide thereinto, a rubber plug in said bore at the inner end thereof, and a rubber bumper on said cap.

HARRY RAFFLES.
